US0D1100519S

(12) **United States Design Patent** (10) Patent No.: **US D1,100,519 S**
(45) Date of Patent: ** Nov. 4, 2025

(54) **PRIVACY SCREEN**

(71) Applicant: **MILLERKNOLL, INC.**, Zeeland, MI (US)

(72) Inventors: **Samuel Hecht**, London (GB); **Kimberlee Colin**, London (GB); **Leo Leitner**, London (GB); **Luca Corvatta**, London (GB); **Michael Katje**, Grand Haven, MI (US)

(73) Assignee: **MillerKnoll, Inc.**, Zeeland, MI (US)

(**) Term: **15 Years**

(21) Appl. No.: **29/912,481**

(22) Filed: **Sep. 19, 2023**

(51) LOC (15) Cl. **06-06**

(52) U.S. Cl.

USPC **D6/332**; D6/714

(58) Field of Classification Search

USPC D6/332, 643, 713, 714
CPC A47G 5/00; G06F 1/1603; A47B 2200/12;

A47B 2220/13
